FLEXIBLE CHAIR BACK CONSTRUCTION

Louis F. Hosek, Chicago, Ill., assignor to Nachman Spring-Filled Corporation, Chicago, Ill., a corporation of Illinois

Application June 1, 1936, Serial No. 82,763

3 Claims. (Cl. 155—179)

The present invention has for its object to provide improvements in chair back constructions of the type illustrated and described in Letters Patent No. 2,020,028 to Darwin Hanauer and in the latter's pending application for patent, Serial No. 32,316, said improvements having for their particular object to provide a resilient elongatable and contractible sustaining or supporting member for the upper resilient rail of the chair back structure per se, as hereinafter more particularly described and pointed out.

In said Letters Patent to Hanauer, the chair back structure comprises a U-shaped frame composed of relatively heavy resilient wire or thin rod, the lower end of said frame being rigidly secured to the side rails and rear end of an ordinary chair frame, while the upper end portions of the arms of said U-shaped frame are free to flex under the influence of load and are connected with each other at their upper extremities by means of a helical spring which constitutes a more resilient and easily flexible element than said upper end portion of said arms of said U-shaped frame.

Owing to the high degree of resiliency and flexibility of said helical spring, it has been found, particularly in the case of upholstered furniture wherein a back supporting spring assembly or cushion structure is carried in large part by the upper end portion of the said U-shaped frame, that the said helical spring is apt to sag under the weight of such portion of the spring assembly as is carried thereby and that this tendency to sag becomes more pronounced when the chair equipped with the said structure and spring assembly is occupied.

To overcome this difficulty and objection is the object of the present invention, suitable embodiments of which are illustrated in the accompanying drawings, wherein,

Fig. 1 is a rear elevation of a chair frame equipped with a flexible back supporting structure including means applied thereto in accordance with the present invention and wherein a spring assembly is shown as mounted upon said structure.

Fig. 2 is a view similar to Fig. 1 showing another embodiment of the invention capable of substitution for the structure of Fig. 1.

Fig. 3 is a perspective view of the front of a chair back structure equipped with means such as are shown in Fig. 1 or Fig. 2 and wherein supporting means for the front wall of the spring assembly of the structure is also illustrated.

Fig. 4 is a fragmentary vertical transverse sec-

tional view of an ordinary chair frame of the type shown in Fig. 3.

Referring to said drawings and particularly to Fig. 1 thereof, it will be noted that the rear uprights or corner posts 1 of an ordinary type of an upholstered furniture chair frame is provided with corner rabbets to receive the lower end portions 2 of the arms of a U-shaped frame 3, the middle portion of which is engaged in a groove in a rear cross-rail 4 of the chair frame. The upper end portions of the said arms 2 of said frame 3 project to a very appreciable distance above the upper ends of the uprights 1 and at their upper extremities are connected with opposed end portions of the cross-rail 5 which, in the instance illustrated in Fig. 1, is composed of a helical spring made of a relatively heavy gauge resilient wire.

Suitable means 6 are provided for firmly securing the U-shaped frame 3 to the chair frame. It will also be noted that a second U-shaped frame 7, having divergent side arms 8, is secured at the upper ends of said arms to the projecting upper end portions of the arms 2 at points very closely adjacent to the upper ends of the corner uprights 1.

A spring assembly 9 of any suitable type, such for example as is illustrated and described in Letters Patent to L. A. Suekoff No. 1,411,227, has its rear wall suitably secured to the said top rail 5 and to the side arms 2 of the U-shaped member 3 along its side portions. The lower end portion of said rear wall is also secured to the said second U-shaped frame 7, the said rear wall of said spring assembly being thus disposed practically in the plane common to the frames 3 and 7. The upper springs included within the spring assembly 9 are of appreciable length, and therefore, naturally tend to sag at their forward end portions particularly under the influence of stresses to which they are subjected.

The spring assembly is generally equipped with a cushion pad, a part of the padding material of which rests upon the top wall of the spring assembly and the remainder of which rests upon the front and side walls of the same and is usually secured to said walls by tufting or in any other suitable manner. The weight of the cushion pad therefor is carried mainly by the forward end portions of the upholstery springs of the assembly and the weight of said cushion pad is also felt appreciably by the top rail 5 of the back structure which sags appreciably under the influence of that weight.

In order to overcome the sagging of the member 5 and also to sustain the front wall and for-

ward end portions of the springs of the spring assembly 9, I have provided sustaining means as illustrated in the several figures of the drawings.

5 In the case of the structure of Fig. 1, I provide a resilient wire upright 10 which is rigidly secured at its lower end to the middle of the lower rail of the frame 7 and which, at its upper end, is equipped with a lateral arm or projection 11 10 which is inserted into the helical spring 5 and contacts with the upper inner faces of the coils thereof.

Between its ends said wire 10 is equipped with a coil 12 extending parallel with the plane common to the frames 3 and 7 and which permits said wire 10 to shorten yieldingly under the influence of weight applied to the spring 5. The normal length of the wire 10 is such that when the spring or rail 5 is relieved of the weight of 20 the spring assembly and padding aforesaid, it will be disposed along its middle portion at an appreciably higher elevation than that which it is shown to occupy in Fig. 1, or, in other words, said rail 5 will be arched under the influence of the 25 pressure of the arm 11 against the same.

The spring assembly 9 is secured to the frames 3 and 7 in such a manner as to forcibly shorten the said wire 10 and bring the rail 5 to the position shown in Fig. 1. Thus the said spring 30 5 is reinforced yieldingly to enable it to carry the normal stresses to which it is subjected without, however, decreasing its resiliency or elasticity or causing it to interfere in any way with the normal flexing of the upper end portion of 35 the arms 2 of the member 3.

Obviously, in place of employing the type of rail 5 shown in Fig. 1, a top rail 13 composed of a very resilient zig-zag wire may be employed as shown in Fig. 2. The ends of said rail 13 are 40 preferably secured to the side arms 2 of the frame 3 by means of welding, though other means of effecting such connection may be employed.

A member 14 composed of resilient zig-zag wire is secured at its upper end portion to the 45 middle portion of the rail 13 and at its lower end is secured by welding, or otherwise, to the middle portion of the frame 7. Thus a very resilient top rail 13 is provided which is suitably supported by the sustaining member 14 to produce the same 50 result as is produced by the structure hereinbefore described with reference to Fig. 1.

In the instance of the structure of both Figs. 1 and 2, I preferably provide also a resilient front top rail 15 composed of very resilient zig-zag wire which is secured by stitching, or in any other 55 suitable manner, to the front wall and preferably also the upper row of springs of the spring assembly 9, such securing means being omitted from illustration herein.

60 The ends of the rail 15 may be suitably secured to the resilient side arms 16 of wire which are bent at their lower end portions to provide rearwardly extending arms 17 secured at their extremities to the side arms 2 of the member 3 by welding, or in any other suitable manner.

65 It will be noted, by reference to Fig. 4, that in the instance illustrated, the spring assembly contains three top rows of six springs each and two bottom rows of four springs each to provide a narrow portion 18 of said spring assembly which lies disposed between the side rails 19 of the chair frame, the lower edge of the spring assembly being generally disposed at about the

level of the rear upper edge of the seat cushion of the chair. The side arms 17 of the corner members 16 are secured by stitching, or in any other suitable manner, so that said upper end portions of the spring assembly containing the 5 three rows of six springs each will be further supported in part by said arms 17.

The advantage of the structure shown in Figs. 3 and 4, taken in connection with the advantages of that of Figs. 1 and 2, lies in the fact that 10 the manufacturer generally supplies the customer with frames 3 and 7 with the spring assembly 9 mounted thereon. These structures are purchased by manufacturers of upholstered furniture units, who incorporate the same into the 15 said units and, because of the resiliency of the component elements of the assemblies so sold to the furniture manufacturers, permits compression of said structures into bales or the crowding of a large number of the same into a relatively 20 small crate for freight rate reduction purposes in shipments from the factory to the customer.

I claim as my invention:—

1. A back supporting structure for seating furniture units comprising a pair of resilient side 25 rail members, a resilient, elongatable cross-rail member secured at its ends to the upper end portions of the side rail members, a conventional spring assembly for upholstery secured along rear side edge portions thereof to said side 30 rail members and along an upper rear edge portion thereof to the said cross-rail member, a resilient elongatable member secured to the upper front corner portion of the spring assembly, and resilient arms secured at their lower ends to said side rail members and at their upper ends to the last-named resilient member.

2. A back supporting structure for seating furniture units comprising a pair of resilient side rail members, a resilient, elongatable and 40 contractible cross-rail member secured at its ends to the upper end portions of the side rail members, a conventional spring assembly for upholstery secured along rear side edge portions thereof to said side rail members and along an 45 upper rear edge portion thereof to the said cross-rail member, a resilient elongatable member secured to the upper front corner portion of the spring assembly, resilient arms secured at their lower ends to said side rail members and at their 50 upper ends to the last-named resilient member, a resilient elongatable and contractible supporting member connected at its upper end to the cross rail member between the ends of the latter, and a support for the lower end of the last-named 55 supporting member disposed in fixed relation to the side rail members.

3. In a chair back structure equipped with resilient side rails, a resilient cross-rail member secured at its ends to the upper extremities of 60 said side rails, a flexible web secured along its side and upper edges to said side rails and to said cross rail member and maintained substantially taut thereby, a resilient substantially vertically disposed supporting member for said 65 cross-rail member secured at its upper end to the said cross rail member between the ends of the latter, and a support for said vertically disposed member secured to the lower end thereof, said last named support disposed substantially 70 at the lower end of said web.

LOUIS F. HOSEK.
